UNITED STATES PATENT OFFICE.

TRUMAN D. COOK, OF TOPEKA, KANSAS.

CARVING, ROUTING, AND MORTISING MACHINE.

SPECIFICATION forming part of Letters Patent No. 554,333, dated February 11, 1896.

Application filed July 31, 1893. Serial No. 482,041. (No model.)

To all whom it may concern:

Be it known that I, TRUMAN D. COOK, a citizen of the United States, residing at Topeka, in the county of Shawnee, in the State of Kansas, have invented certain new and useful Improvements in Carving, Routing, and Mortising Machines, of which the following is a specification.

My invention relates to improvements in carving, routing, and mortising machines in which a boring and routing bit is used to produce routing, mortises, tenons, rabbets, chamfers and the like; and the objects of my improvements are, first, to provide a means by which, while the frame carrying the bit is stationary, the material to be operated upon may be carried about, under, and against the bit in such manner that the bit may at all times cut with precision and accuracy to a line determined by the line of the pattern, regardless of the size of the bit; second, to provide an adjustable compensating guide-pin adapted by its adjustment to compensate the loss in diameter of the bit due to wear and sharpening, 25 that with a given pattern and bit the lateral dimensions of the routing, &c., may be exactly retained; third, to provide a pattern-board having the pattern so constructed therein with reference to the guide-pin that when 30 the line of the pattern follows the guide-pin the routing, &c., of the desired lateral dimensions, shall be produced in the material regardless of the size of the guide-pin and of the bit; fourth, to provide means for securing 35 the guide-pin adjustably in the operating-table; fifth, to provide an adjustable guide-pin adapted by its adjustment to the production from a given pattern of the routing, &c., of any desired lateral dimensions, without regard to the lateral dimensions of the pattern 40 or the size of the bit.

My improvements are made with special reference to my patented carving and routing bit, Letters Patent for which were granted to me April 20, 1886, No. 340,100; or they may be used with any other bit of like character and operation.

I obtain the objects of my invention by the mechanism illustrated in the accompanying drawings, in which—

Figure 1 is an isometrical projection of the machine with part of the table removed, as

indicated by the dotted lines, showing the working parts underneath and in detail. Fig. 2 is a vertical projection with cross-section, 55 showing the manner of securing the bit and guide-pin and their respective working parts. Fig. 3 is a cross-section of the bit and chuck in which it is secured. Fig. 4 is a cross-section of the guide-pin, showing the manner of 60 its operations and of securing it to the table. Fig. 5 is same as Fig. 4, except that it shows a straight guide-pin. Fig. 6 is a pattern-board in perspective, showing a pattern therein.

I preferably use the tapering guide-pin 65 shown in Fig. 4, but do not limit myself to any particular or peculiar size or shape of pin.

Similar figures refer to similar parts throughout the several views.

1 is a floor-plate resting upon and adapted 70 to be secured to the floor.

2 2 are the posts or standards upon which are mounted the arms 3 3, having the terminal bearings 4 4, in which is journaled the vertical shaft 7. The shaft is provided between the bearings with the pulley 5 and at 75 its lower end bears the chuck 8, in which is set the boring and routing bit 9, secured therein by the set-bolt 27. Power is transmitted through the belt 6, passing around the pulley 80 5, over the pulley 43, supported by the bracket-hanger 42, and a like pulley on the opposite side of the posts (not shown in the drawings) and about the band-wheel 44, carried on the driving-shaft 45, one of the bearings of which 85 is shown at 46. The shaft 7 and its bit 9 may be driven at as high a rate of speed as ten thousand revolutions per minute, though for regular steady work four thousand to five thousand revolutions are sufficient. 90

To the standards is secured the plate 12, the lateral edges of which extending beyond the standards are clasped by the embracing vertical arm of the table-support 11, adapted to slide up and down thereon and upon its 95 horizontal arm, carrying the table 10. Upon the table is supported the pattern board or form 47, having the handles 48, the horizontal part of which also secures the material to the board, the slot 49 of the pattern it is desired the bit should follow and produce in the material to be operated upon, and the ears 51 to retain the material in position. 100

23 is the guide-pin set in a depressed re-

ceptacle in the upper bed-plate 22, which is set in the table so that its upper face is flush with the face of the table. The depth of the 5 guide-pin in the receptacle is determined by the set-bolt 24 entering the receptacle from below and upon which the pin rests, said bolt being threaded into the lower part of the bed-plate and provided with a hand-wheel 25.

22^a is the under bed-plate.

10 26 is a nut-lock provided with a handle. When tightened up, it secures the plates to the table by compression of the table between the shoulder of the upper and the edge of the lower bed-plate. Being set upon the set-bolt, 15 when tightened it securely locks the bolt and prevents it loosening by the jar of the machinery. The table is adjustable vertically to determine the depth the bit shall enter the material. This adjustment is effected by 20 means of the engagement with the rack 12 on the vertical arm of the table-support of the ratchet 14 on the vertical arm 13 of the reciprocating lever 15, having its fulcrum at 16 upon the floor-plate and provided with the 25 foot-plate 16^a, said lever working between the upright guides 17, and its action in the vertical adjustment of the table being regulated by pins in said guides. The ratchet 14 is detained in its engagement with the rack 12 by 30 the flat spring 18, secured to the under side of the horizontal arm of the table-support and to the vertical arm of the lever by the bolt 50 sliding between the two parts of the arm, and is released by means of the rod 19, having its 35 inner end secured near the extremity of the flat spring, and provided with the teeth or rack 20, engaging the edge of the opening in the hanger 21, through which it passes.

The more exact adjustment of the table is 40 effected by means of the vertical screw 28, the lower end of which rests in the foot-step 29, secured by the plate 30 to the standards. The screw of the gage threads in the receiver 31, secured in the bracket 32, attached to the 45 vertical rack-arm of the table-support. At its upper end it passes through the sleeve 35 set in the bracket extension 34 of the arm 33, and is provided with the gear-wheel 36, loosely keyed thereto to admit of the vertical 50 passage of the shaft through the wheel. The gear-wheel 36 meshes with the gear-wheel 37 on the shaft 38, journaled at its inner end in the bearing 37^a and at its outer end in the bearing 39 on the extremity of the arm 33 55 and provided with the wheel 40 having the handle 41.

In the operation of my improved machine any design required or desired may be laid off in the pattern-board, and the material being secured to the board the bit acting directly over the pin and the pattern following the pin, if the pin and the bit be all of the same dimensions the pattern is exactly reproduced in form and dimensions in the material, the 60 depth to which it is cut being determined by the vertical adjustment of the table. If, however, it is desired to cut a furrow, rout-

ing-rabbet, or other form in the material of greater lateral dimensions than the diameter of the bit, it may be done without changing 70 the bit by the use of my adjustable tapering guide-pin. Thus the pattern-slot and the bit remaining the same, the tapering guide-pin being depressed in its receptacle by resetting the set-bolt, the edge of the pattern-slot is allowed to pass laterally until the bit cuts to the desired line on one side. Then reversing the direction of the movement of the pattern-board and passing the other edge of the pattern-slot along the guide-pin the bit will cut to 80 the desired line on that side also and the pattern in the pattern-board will be reproduced in the material of the width desired. This constitutes a second very important advantage 85 in my improvement.

A third very important advantage obtained by my tapering guide-pin is that when the bit becomes worn by use and sharpening, by depressing the pin by lowering the set-bolt this loss is compensated and the line of the 90 pattern brought true to the line of the bit, and the pattern perfectly and exactly reproduced in the material secured on the pattern-board under the bit, whereas without this adjustment of the guide-pin the line produced 95 by the bit would vary from the line of the pattern according to the wear of the bit, and the bit have to be replaced by a new one. I preferably use the tapering guide-pin shown in Fig. 4. I, however, reserve the right to use 100 a straight pin, as shown in Fig. 5, or any other form of pin adapted to the use required, not intending to limit my invention to the form of pin.

Having thus described my invention, what 105 I claim as new, and desire to secure by Letters Patent, is—

1. In a carving, routing, and mortising machine a guide-pin set in a depressed receptacle of an upper bed-plate and adjustable therein 110 by a set-bolt entering the plate from below an under plate partly encircling the upper plate, a nut-lock carried on the set-bolt securing the plates to the table and locking the set-bolt, with the vertically-adjustable table and 115 pattern-board carried thereon in combination substantially as shown and described, and for the purposes specified.

2. In a carving, routing and mortising machine the combination of a guide-pin set in a 120 depressed receptacle of an upper bed-plate and adjustable therein by a set-bolt entering the plate from below an under plate partly encircling an upper plate, a nut-lock carried on the set-bolt securing the plates to the table 125 and locking the set-bolt, a vertically-adjustable table in which the plates carrying the guide-pin are secured and a pattern-board carried on the table, with a boring and routing bit set in a chuck secured in a vertically-revolving shaft substantially as shown and described, and for the purposes specified.

3. In a carving, routing and mortising machine a vertically-adjustable table having set

in it a guide-pin and carrying a pattern-board the pattern in which is adapted to follow the guide-pin, said table carried on the horizontal arm of a bracket-support the vertical arm of which embraces and slides upon a plate secured to the standard and is provided with a rack with which engages a ratchet on the arm of a reciprocating adjusting-lever, a spring attached to the horizontal arm of the bracket-support and secured to the ratchet-arm to detain the ratchet in engagement with the rack, a rod to release the engagement, and a vertical screw threaded in a sleeve or receiver set in a bracket attached to the rack-arm, its lower end resting in a foot-step and provided at its upper end with a loosely-keyed gear-wheel meshing with a similar gear on a horizontal shaft provided with a wheel and handle within reach of the operator, in combination substantially as shown and described, and for the purposes specified.

4. In a carving, routing and mortising machine the combination of a vertically-adjustable table having set in it a guide-pin as shown

and described carrying a pattern the pattern in which is adapted to follow the guide-pin, said table being carried on the horizontal arm of a bracket-support the vertical arm of which embraces and slides upon a plate secured to the standard and is provided with a rack with which engages a ratchet on the arm of a reciprocating adjusting-lever, a spring attached to the horizontal arm of the bracket-support and secured to the ratchet-arm to detain the ratchet in engagement with the rack, a rod to release the engagement, a vertical screw secured to the rack-arm its foot resting in a foot-step and means provided near its upper end and within reach of the operator for operating it, of a carving and routing bit set in a chuck secured in a vertical shaft, and means for rotating the shaft substantially as shown and described, and for the purposes specified.
